METHODS FOR MAKING PERFORATED-EMBOSSED LEATHER FABRICS

Abraham R. Kaplan, Great Neck, N. Y.

Application November 16, 1953, Serial No. 392,439

6 Claims. (Cl. 41—24)

The present invention relates to methods for forming 15 perforated and especially perforated-embossed leather or similar fabrics, particularly decorative, perforated-embossed leather or like fabrics, such as are described and claimed in my companion application, executed of even date herewith, entitled "Perforated-Embossed Leather or Like Fabrics and Apparatus for Forming the Same," and which find preferred use in shoe uppers or the like.

In my said companion application, I have explained that perforated decorative fabrics have heretofore been made and used, and that such prior art fabrics have heretofore been made by the die-cutting method; each perforation being formed by an individual, tubular cutting knife which struck or punched out a section of the fabric to form the perforation and which was assembled with a number of companion tubular or circular knives into 30 a single cutting die.

In my said companion application I have also explained the shortcomings and limitations resulting from the practice of the prior art methods, among which were listed limitations on the minimum size of the perforations because of the physical limitations on the minimum size of a tubular or circular knife that could be made; limitations on the minimum space between perforations due to the limits on the proximity in which adjacent circular or tubular knives could be assembled; and, finally, limitations of the strength of the resulting decorative fabric due to the removal of sections thereof in the formation of the perforations.

Another shortcoming in the prior art methods and apparatus, not adverted to in my said companion application, is that with such methods and apparatus it was generally necessary to form and provide a separate cutting die for each different size or shape of perforated area desired to be formed, even though the size and shape of the individual perforations remained the same. This rendered variation in the size and shape of the area perforated with a particular size and shape of perforation practically prohibitive from the point of cost.

It is an object of the present invention to devise methods for making perforated-embossed leather or like fabrics of the character described which will not materially weaken the tensile strength of the perforated leather or fabric.

It is also an object of the present invention to devise methods of the character described which, while forming perforations in the leather or fabric, will strengthen the portions of the fabric between perforations, to compensate, at least to a major extent, for any weakening that might result as a consequence of the formation of the perforations.

It is a particular object of the present invention to devise methods whereby leather or like fabrics may be provided with perforated or perforated embossed areas of different sizes and shapes from a common die, without any need for preparing a separate die for each differently sized or shaped perforated area that might be desired

2

to be made, enabling great flexibility in decorative design with great economy.

It is a further object of the present invention to devise methods of the character described which are simple, easy and economical to practice.

The foregoing and other advantages and superiorities of the methods of the present invention will become more readily apparent to those skilled in the art from the embodiment and arrangement of one form of the apparatus of the present invention for use with such methods, shown in the accompanying drawing and from the description following. It is to be understood, however, that such embodiment is shown by way of illustration only, to make the principles and practice of the invention more readily comprehensible, and without any intent to limit the invention to the specific details therein shown.

In the drawings:

Fig. 1 is a more or less diagrammatic, exploded, perspective view showing a die for use with the methods of the invention and the relative arrangement of the leather and other elements with respect to it, in practicing the method;

Fig. 2 is a more or less diagrammatic, cross-sectional view, showing the arrangement of die and work at the end of the perforating embossing process; and

Fig. 3 is a perspective top plan view of a section of leather or like fabric having a perforated-embossed area of limited size and shape formed on the die of Fig. 1.

Generally stated, the present invention departs from the methods of the prior art which form the perforated decorative fabrics by punching or cutting out sections of the fabric, in forming such perforated decorations by punching or piercing operation and a gradual enlargement of the punctured or pierced openings. Such methods of puncturing and spreading leaves the leather or like fabric material intact, merely transposing or shifting some of it to the sections of the fabric between and immediately adjacent to the punctured perforations, thus affecting the strength of the leather or like fabric to a minimum.

Another departure of the methods of the present invention from the methods of the prior art resides in the formation of decorative perforations that vary taperingly in cross-section from one surface of the fabric to the other, so as to produce a product which has large, clearly visible and distinct perforation openings in one of its surfaces but relatively smaller, less exposing openings in its other surface. Such method of perforation also leaves webs between perforations that are of relatively greater strength in proportion to the proximity of the perforations to one another on the side of their larger openings.

For the practice of the methods of the present invention, I have devised a die, generally designated as 10, which may be formed of any suitable metal, such as bronze, which has cut out in one of its surfaces, a plurality of puncturing teeth or elements, 11. Such elements are formed with relatively wide bases and taper outwardly, preferably gradually an end or point 12, of adequate sharpness to penetrate, under suitable pressure, the leather or like fabric to be perforated and also the masking material which will hereinafter be more fully described.

The puncturing elements 11 are preferably of a height greater than the thickness of the leather or like fabric to be perforated and any lining that may be provided with it, and may be of circular cross section or of polygonal cross section, as triangular or quadrilateral, as illustrated; having relatively sharp edges, 13, for ease of penetration and for forming perforations of sharp and distinct outline. The puncturing elements may be

formed in the die 10 in any desired pattern, such as an overall pattern or one in which the elements 11 are arranged in groups, depending on the design desired to be formed.

In the practice of the present invention, a die, such as 10, is preferably placed, elements 11 up, on a work table, as of a press. A section of leather or like fabric, lined or unlined, designated as 15, is then placed on the die 10, with its obverse or outer face, 16, resting on the elements 11. A masking sheet or plate, 18, of a suitable material, such as a material with innate resilience or that can be readily penetrated by the puncturing elements 11, as of cardboard or the like, of adequate thickness, is then rested on the reverse face, 19, of the fabric 15, directly over the elements 11 of the die, and the press, 20, is then lowered on the masking board 18, and pressure applied until the puncturing elements 11 are forced through the leather or like fabric 15 and to the desired depth into the masking board 18, to obtain perforations, 21, of the desired size.

During the pressing operation, the elements 11 will first penetrate and puncture the fabric 15, without removing any part thereof, and will gradually enlarge the penetrations to form the perforations 21, displacing the fabric material laterally to compress it into the webs 22, between perforations; such webs being thickened as well as compressed, with the thickening taking place on the side away from the masking board 18, by being forced into the spaces between elements 11, to form tapering embossments.

It will be apparent that the perforations 21 will taper correspondingly to the elements 11 and will have wide openings in the obverse face of the leather or like fabric 15 and smaller openings in the reverse face 19 thereof.

The foregoing method, when used with the apparatus of the present invention, as illustrated and described, because of the sharp ends 12 of the elements 11, may be readily adapted to form perforated areas in leather or like fabrics, of different sizes and of different shapes or outlines, with the same die. This may be readily accomplished by forming a masking board 18 of the exact size and shape or outline desired to be formed in the fabric, and by utilizing such masking board in the manner described, to dispose it directly over the portion of the leather or like fabric desired to be perforated. In this manner, when pressure is applied, it will be transmitted and applied only through the masking board 18, of limited size and shape, only over the teeth directly underlying it, puncturing only that portion of the leather or like fabric 15 lying between it and the elements 11, leaving the surrounding area of the leather or like fabric imperforate because of lack of pressure on it. This is not readily possible with circular or cylindrical cutting or punching teeth having end areas of substantial size that it would be difficult to match with the edges of a masking board such as 18.

In the illustrative embodiment of the invention shown in the drawing, although the die 10 is of relatively larger, rectangular shape, the masking board 18 is shown as being of smaller size and as having the shape of half an octagon, and the fabric 15 is shown in Fig. 3 as having received a perforated area resulting from the use of such masking board which is of identical size and shape as the masking board.

It may here be stated that wherever the term "leather" is used in the claims, it is intended to include both, natural and artificial leather and leather substitutes.

This completes the description of the methods of the present invention. It will be readily apparent that such methods are highly suitable for forming decorative per-

forated fabrics of improved characteristics; that such methods are easy and simple to practice; and that they enable the utilization of one die for making perforated areas in fabrics of many different sizes and shapes.

5 It will also be apparent that numerous modifications and variations may be made in the methods of present invention by any one skilled in the art, in accordance with the principles of the invention hereinabove set forth and without the utilization of any inventive ingenuity. I 10 desire, therefore, to be protected for any and all such modifications and variations that may be made within the spirit of the present invention and the scope of the claims hereto appended.

What I claim is:

1. The method for forming a decorative perforated leather fabric which comprises the steps of simultaneously puncturing the fabric at a plurality of points and gradually taperingly enlarging said punctures.
2. The method for forming a decorative perforated leather fabric which comprises the steps of placing the fabric over a plurality of tapering puncturing teeth and simultaneously gradually forcing said teeth through said fabric.
3. The method for forming a decorative perforated 25 embossed leather fabric which comprises the steps of placing the fabric on a die having a plurality of sharp pointed tapering puncturing teeth with the teeth disposed against the fabric, placing a masking board of material penetrable by said teeth against said fabric over said teeth and applying pressure against said masking board.
4. The method for forming a decorative perforated embossed leather fabric which comprises the steps of placing the fabric on a die having a plurality of sharp pointed teeth, with the fabric disposed against the points of said teeth, placing a masking board of a material penetrable by said teeth and pressing said die and said masking board toward one another.
5. The method for forming a perforated area of limited size and shape in a leather fabric which comprises the 40 steps of forming a masking board of a material penetrable by puncturing teeth of the same size and shape as the said perforated area, placing the fabric on a die having a plurality of tapered puncturing teeth with the area to be perforated disposed on the points of said teeth, placing said masking board over the area of the fabric to be punctured and then pressing said die and said masking board toward one another.
6. The method for forming a perforated area of any 45 selected size and shape in a leather fabric on a common die having a plurality of tapered, pointed puncturing teeth which comprises the steps of forming a masking board of a material penetrable by said teeth of the shape and size of the selected area to be perforated, placing said fabric against said die with the area to be perforated disposed completely against said teeth, placing said masking board over the area of said fabric to be perforated and pressing said die and said masking board toward one another.
